UNITED STATES PATENT OFFICE.

ROBERT D. BEATTY, OF BIRMINGHAM, ALABAMA.

DUST-DISTRIBUTING CAR.

Application filed December 29, 1924. Serial No. 758,750.

To all whom it may concern:

Be it known that I, ROBERT D. BEATTY, a citizen of the United States, residing at Birmingham, in the county of Jefferson and 5 State of Alabama, have invented a new and useful Dust-Distributing Car, of which the following is a specification.

This invention aims to provide a novel form of distributing car which may be used 10 for "rock dusting" coal mines, the invention comprising novel means for feeding the dust from the car, and for distributing the dust in the mine.

It is within the province of the disclosure 15 to improve generally and to enhance the utility of devices of that type to which the invention appertains.

With the above and other objects in view which will appear as the description 20 proceeds, the invention resides in the combination and arrangement of parts and in the details of construction hereinafter described and claimed, it being understood that changes in the precise embodiment of the invention herein disclosed may be made within 25 the scope of what is claimed, without departing from the spirit of the invention.

In the accompanying drawings:—Figure 1 shows in top plan, a device constructed in 30 accordance with the invention; Figure 2 is a side elevation; Figure 3 is a longitudinal section on the line 3—3 of Figure 1; Figure 4 is an end elevation; Figure 5 is a transverse section; Figure 6 is a section taken on 35 the line 6—6 of Figure 1; Figure 7 is a section taken on the line 7—7 of Figure 1.

The car comprises a body 1 which may be made in various ways, without jeopardizing the utility of the invention. As shown, but 40 not of necessity, the body comprises ends 2 and 3, sides 4 and downwardly and inwardly slanting bottom members 5. End cross pieces 6 and intermediate cross pieces 7 are connected to the bottom members 5.

45 The frame 8 of the car, like the body 1, may be made in many ways within the scope of the invention. In order to present a concrete embodiment, the frame 8 is delineated as including side bars 9 and end bars 10. End posts 11 and intermediate posts 12 are connected to the side bars 9 of the frame 8, and, through the instrumentality of brackets 14, the end posts 11 of the frame 8 are joined to the end cross pieces 6 of the body 1, the intermediate posts 12 being similarly connected to the intermediate

cross pieces 7 of the body 1. Axles 15 are supported at 16 on the side bars 9 of the frame 8, and carry wheels 17 adapted to move along a track 18.

At the longitudinal center of the body 1 and at the lowermost portion of the body is located a trough-like member 19 which extends longitudinally of the car, the member 19 having lateral flanges 20 which are connected to the body forming members 5. At one end, the trough-shaped member 19 is closed, as shown at 21, in Figure 3 by a portion of the end 3 of the body 1, the opposite end of the member 19 communicating with a vertical chute 22, as shown at 23, the chute being mounted on the end 2 of the body 1. As shown at 24, the chute 22 communicates with a conduit 24 which extends through the lower portion of the chute, the conduit being disposed longitudinally of the car. Above the conduit 24, the chute 22 carries a removable screen 25.

The conduit 24 has an upwardly extended end 26 communicating with a suction and blower mechanism 27 mounted on a platform 28 carried by the side bars 9 of the car frame 8. The shaft 29 of the suction and blower mechanism 27 is coupled, as shown at 30, to the shaft 31 of a motor 32 mounted on the platform 28. The motor 32 may be of any desired sort, but it is suggested that an electrical motor be used if considered desirable. The shaft 29 of the suction and blower mechanism 27 carries a beveled pinion 33 meshing with a beveled gear 34 on a shaft 35 extended longitudinally of the car, the shaft being journaled in a bearing 36 on the platform 28. At its inner end, the shaft 35 is supplied with a beveled pinion 37 meshing with a beveled pinion 38 on a shaft 39 disposed transversely of the car, the shaft 39 being journaled in a casing 40 supported by a hanger 41 on the end 3 of the car body 1.

Within the casing 40, the shaft 39 is 100 equipped with a worm 42, meshing with a worm wheel 43 on a shaft 44 extended longitudinally of the member 19 and journaled in the casing 40, in the part 21 of the end wall 3 of the car body, and in the chute 22. The shaft 44 carries a screw conveyor 45 operating in the trough-like member 19 of the car body.

Disposed above the screw conveyor 45 is a grate 46, in the form of an inverted angle member, extended between the ends 2 and 3 and supported upon and connected

to the downwardly sloping bottom members 5 of the body 1. A slide 47, in the form of an inverted angle member, is mounted for reciprocation on the grate 46, the slide 47 and the grate 46 being equipped with openings 48 which are adapted to be brought into registration when the slide is moved endwise. The slide 47 carries laterally extended rakes 49, which move in close proximity to the bottom members 5. At one end, the slide 47 has an arm 50, mounted to reciprocate in the end 2 of the car body 1, the arm 50 being connected in any suitable way, as shown at 51, to the lower end of an operating member 52, preferably a lever, the lever being fulcrumed intermediate its ends, as shown at 53, on the end 2 of the car body 1.

In practical operation, the finely divided material with which the mine is to be dusted, is placed in the car body 1. Through the medium of the lever 52, the slide 47 may be moved endwise, so as to bring the openings 48 to the slide and of the grate 46 more or less into registration, thereby to regulate the amount of material which passes downwardly into the trough-shaped member 19, and to cut off the supply of material to the trough-like member 19, upon occasion. The material, passing through the openings 48 of the slide 47 and the grate 46, is engaged by the screw conveyor 45 and is advanced to the right in Figure 3, the material passing into the vertical chute 22, the screen 25 exercising its obvious office. From the chute 22, the material passes through the opening 63 into the conduit 24, and when a blast of air passes through the conduit, the dust or material is driven out into the mine and distributed through a suitable nozzle (not shown).

The blast of air through the conduit 24 is created, of course, by the suction and blower mechanism 27, the shaft 29 of the suction and blower mechanism being driven

from the shaft 31 of the motor 32. The driving train for the shaft 44 which carries the conveyor 45 includes the beveled pinion 33, the beveled pinion 34, the shaft 35, the beveled gear 37, the beveled gear 38, the shaft 39, the worm 42, and the worm wheel 43.

Having thus described the invention, what is claimed is:—

1. In a device of the class described, a wheel-mounted frame, a body carried by the frame, a blast conduit supported by the frame, means for producing a blast in the conduit, a conveyor in the body and discharging into the conduit, means for operating the conveyor, and mechanism for regulating the flow of material from the body to the conveyor, said mechanism being movable under the control of an operator and including a rake adapted to move along the bottom of the body.

2. In a device of the class described, a wheel-mounted frame, a body on the frame and provided in its bottom with a trough-shaped member, a grating located in the body over the trough-shaped member, a conveyor operating in the trough-shaped member, the conveyor being practically equal in length to the body, and the grating being practically equal in length to the conveyor thereby to secure an even supply of material to the conveyor, a perforated slide mounted to reciprocate on the grating and governing the flow of material from the body to the conveyor thereby to avoid a clogging of the conveyor, a longitudinal blast conduit into which the trough-shaped member discharges at one end, means for supplying a blast to the conduit, means under the control of an operator for moving the slide, and means for operating the conveyor.

In testimony that I claim the foregoing as my own, I have hereto affixed my signature.

ROBERT D. BEATTY.
